GOOGLES STRUCTURE

William R. Christensen, Newton Highlands, and
Chester E. Cross, East Sandwich, Mass.

Application June 8, 1949, Serial No. 97,862

6 Claims. (Cl. 2—14)

(Granted under the act of March 3, 1883, as
amended April 30, 1928; 370 O. G. 757)

1

The invention described herein, if patented, may be manufactured and used by or for the Government for governmental purposes without the payment to us of any royalty thereon.

This invention relates to improved goggles, and particularly to an improvement in goggles frame structure and lens arrangement, to prevent fogging and frosting under conditions of low ambient temperatures.

Broadly, in principle, goggles, to be efficient under conditions of usage wherein climatic moisture and temperature conditions induce fogging and frosting, must be provided with adequate and proper air flow means. This air flow means must be designed to induce a flow of air coinciding with the normal convection currents of the goggles cavities in so far as possible, to provide for ready and rapid removal of moist air which tends to collect upon the goggles lenses without producing undue chilling of the eyes.

Accordingly, it is an object of this invention to provide an improved anti-fogging and anti-frosting goggles structure.

It is another object of this invention to provide an improved controlled air flow through a goggles structure.

It is a further object of this invention to provide an improved anti-fogging and anti-frosting goggles structure wherein there is constant and rapid removal of excessive humidity entrapped within the goggles cavities without an undue chilling of the eyes.

It is a further object of this invention to provide an improved goggles structure wherein constantly controlled currents of air admitted from the exterior coincide with normal convection currents within the goggles cavities to continuously and rapidly remove excessive moisture from the eye-cups.

Further objects, advantages, adaptations and uses of this improvement in goggles structure will be readily apparent from the following description of the accompanying drawings, wherein:

Figure 1 is a front elevational view of a goggles structure embodying the invention;

Figure 2 is a top view of the goggles shown in Figure 1;

Figure 3 is a cross-sectional view on line 3—3 of Figure 1;

Figure 4 is a fragmentary perspective view of the goggles' ventilating structure; and

Figures 5 and 6 are sectional views of blanks which form air passageways for the goggles structure.

Referring to the drawings, the goggles frame 10

comprises a conventional flexible, rubber-type frame structure, having a resilient face-contacting body portion 11 and extended rib 12, provided with bead 13, within which is a flexible lens-holding groove 14.

As indicated, the goggles frame structure 10 is of conventional rubbery material and the groove 14 is adapted to be flexed for insertion of goggles lenses 15 in the usual and conventional manner.

10 In addition to the groove 14, there are provided conventional snap fasteners 16 and 17 adapted to clamp the goggles lenses into place likewise in a conventional manner. The goggles frame 10 is also provided with a conventional head strap 18, having its ends secured in the lugs 19 of the usual character.

For purposes of description, the goggles ventilator 20 is shown as formed from thin, flexible copper sheets or strips 21, 22 and 23, cut and bent to provide a parallel series of air ducts or

20 passages 24 and 25. The air ducts 24 are formed by folding the blank 21 on the dotted lines 21', to provide a plurality of uniformly spaced accordion folds forming partitions 26' cooperating with the

25 portions 26 of the strip 21 and the extensions 28 depending from the portions 26 to form the inlet passages 24. Extensions 28 are of dovetail shape (Fig. 5) so that they overlap along their lateral edges 28' when the accordion folds 26' are formed in the strip and thus provide a continuous back wall portion for the inlet passages 24 which is inclined forwardly as best seen in Fig. 3 to direct incoming air toward the inner side of lens 15.

A baffle or shield over the inlet to the inlet passages 24 is formed by dovetailed shaped ears 27 or baffle extensions 27 on the portions 26 of the strip 21. These extensions are bent forwardly over the inlet ends of inlet passages 24 and overlap along their lateral edges 27' to form a continuous shield or baffle for directing air into inlet

30 passages 24. By varying the spacing between the extensions 27 and the inlet ends of the passages 24, the amount of air admitted through inlet passages 24 can be varied.

The air passageways 25 constitute air outlets and are formed by bending the thin, flexible copper blank 22, on the dotted lines 22', to provide a plurality of accordion folds or projecting ribs 30 connected by wall portions 29. The projecting, angularly sloping ribs 30, are uniformly spaced along strip 22 and have an upwardly and backwardly inclined upper edge formed by an angular V-shaped center cut of the extension on blank 22, as illustrated in Fig. 6. Attached to this upper edge of the ribs 30 is the thin metallic strip

23, having accordion folds 31 at equally spaced intervals to coincide with and serve as a means for attaching the strip to the ribs 30. As illustrated in Fig. 4, the strip 23 inclines upwardly and rearwardly over the top of air passageways 25 so that they are open on their rear side only.

After bending or shaping the blanks 21, 22 and 23, they are joined together as a unitary structure in the manner illustrated by the partial view of Fig. 4. The lower end portions of ribs 30 are aligned with the interior V's formed by ribs 26' and the end portions 32 of the strip 21 are bent to overlap end portion 30' of strip 22 and thereafter sealed, as by welding or use of an adhesive as cellulose acetate or the like. The prefabricated strip 23 is secured to the prefabricated strip 22 by a suitable adhesive or welding together of the ribs 31 and 30, respectively, and the end 31' is suitably sealed in overlapped relationship to the rib 30'. The extensions 28 and their lateral edges 28' rest somewhat loosely in overlapping position to provide an air-directing and distributing unit within the goggles cavities.

In order to insert the assembled ventilator 20 into goggles frame 10, a longitudinal opening in rib 12 is provided substantially across the entire top of the goggles structure and of substantially the exact size of the ventilator 20, whereby it may be inserted and sealed within this opening in the goggles. The back wall portions 29 of strip 22 and the edges of partitions 26' of strip 21 are sealed directly at their contacting portions to the walls of the opening in rib 12 by a suitable rubber or cellulosic adhesive or the like, of a sufficiently flexible nature to permit normal goggles flexibility.

In conjunction with the ventilator 20 there is provided a transparent partition 33 as more clearly shown in Fig. 3, having a bottom edge 35 spaced upwardly from the bottom of the frame 10 so as to establish communication between the opposite sides of partition 33. The partition 33 is secured within the goggle frame 10 by a suitable spacing gasket 34, which is preferably secured by suitable rubber adhesive or the like, to hold the partition 33 in place. The top portion of the partition 33 is fitted in the grooves or slots 36 in the forward edge of the partitions or ribs 30 that are formed by folding strips 22 along the lines 22' as previously described. When so positioned, the partition 33 is not in airtight relationship with the backing or median plate 26 and the flared edges 28', which flared edges 28', in conjunction with the lower edges 28 of the backing 26, extends forwardly toward the partition 33, as illustrated so as to direct and evenly distribute incoming air from the passageways 24 over the inner area of the partition 15 and the outer area of partition 33. In addition, the forwardly inclined extensions 28 are not in airtight contact with each other or with the partition 33 so that egress is provided through outlet passageways 25 for moisture tending to collect about the upper surface of the partition 33 under and about the back wall of inlet passages 24. Further, the metallic extensions 28 serve as heat conductors to aid in maintaining lower non-condensing temperatures within the goggles frame.

With the ventilator 20 secured in the upper portion of the rib 12 and extending substantially across the top of the goggles frame, as described, the air inlet conduits 24 are at the forward side of frame 10 with the free end of inlet baffles 27 extending forwardly to form an adjustable inlet producing a steady and continuous flow of air into

the goggle cavities in the manner described. Thereafter, the air passes downwardly between the lens 15 and partition 33 and thence passes under the lower edge 35 of the partition and then passes upwardly, both by convection and the pressure of incoming air, and out of the goggles cavities through outlet passageways 25. When the goggles are adjusted into position about the eyes, this flow of air, passing over the inner side of lens 15 and both sides of partition 33, rapidly carries off any moisture developing from excessive humidity conditions. As indicated, the volume of flow or passage of air is controlled by bending the baffles 27 toward or from the upper end of inlet passages 24. Under relatively windy conditions the baffles 27 may be substantially closed by being pressed against the bead 13 and the flared lateral edges 27', then serve to permit a passage of sufficient air to keep the goggles clear, as may be determined by the wearer. Under comparatively quiet or non-windy conditions, the extensions or baffles 27 may be opened by bending them upwardly from the bead 13 and the normal convection currents induced by normal heat conditions due to wearing will cause air within the goggles eye-cups to pass outwardly through the passageways 25, creating somewhat of a vacuum or suction between the lenses 15 and partition 33, which thereby draws new air into the goggles through passageways 24. The relative angular position of the member 23 on ribs 30 provides protective means for outlet passageways 25, so that under normal and excessive wind conditions a reverse air flow within the goggles is prevented.

If desired, or if the goggles structure is to be used with additional glasses, the face contacting body portion 11 may be built up or padded with an extra layer or layers of padding 11', secured by a suitable rubber cement or the like. In its construction the body 11 may be enlarged or the padding added to provide more cavity area within the goggles.

Having thus described the ventilator, it will be apparent that a somewhat modified, molded or otherwise assembled construction, in the nature of that described and formed from rubber, resin, or other flexible materials, fitted with an adjustable air passageway cover means, including the use of transparent flexible or non-flexible air guide means as a substitution for the air guides 28 and 28', may be provided.

Therefore, while the invention has been described in more or less detail, it is not to be limited thereby, as changes may be made in the form, arrangement, and construction of parts, and equivalents may be substituted, without departing from the spirit and scope of the invention as claimed, the forms hereinbefore described being merely preferred embodiments thereof.

We claim:

1. In a goggles having a lens supported in a frame which has a flexible face contacting part cooperating with the lens to define substantially sealed eyecups when the goggles are worn, the combination comprising, ventilating air inlet and outlet forming means for said eyecups extending through the top side of said frame and each comprising passage forming means, and a transparent partition in said frame behind said lens extending from one side of said frame over at least a major portion of the area of the frame to define a relatively narrow space behind said lens communicating with the atmosphere through said inlet forming means and with the space in

said eyecups at the rear of said partition containing air in contact with the face of a wearer at a region opposite said inlet forming means so that the flow of ventilating air entering the inlet forming means is confined to said narrow space, said outlet forming means also communicating with the space in said eyecups behind said partition to provide for the escape of air from the said space and consequently to promote a flow of fresh ventilating air from said inlet forming means through said narrow space and to the space behind the partition.

2. In a ventilated goggles having a frame including a part for holding a lens and an integral flexible face contacting part cooperating with a lens supported in the frame to define a substantially sealed space behind the lens when the goggles are worn, the combination comprising, ventilating air inlet and outlet forming means for said sealed space each comprising wall structure forming a plurality of flexibly interconnected passages arranged in side-by-side relation in parallel front and rear rows extending through the top side of said frame longitudinally thereof, a transparent partition in said frame behind said lens, cooperating therewith to form a narrow space behind the lens, said narrow space communicating with the atmosphere through the front row of passages and with the sealed space to the rear of said partition adjacent the lower-most regions of said spaces and said space to the rear of said partition communicating with the atmosphere through said rear row of passages, and flexible baffle structure on the outer end of said passages to direct air through the front row of passages into said narrow space and to promote convectional flow of air warmed by contact with the wearer's face to the exterior through the rear row of passages.

3. A goggles as defined in claim 2 wherein the inlet and outlet forming means and the baffle structure is formed from material of high thermal conductivity.

4. A goggles as defined in claim 2 wherein the flexible baffle structure over said inlet means comprises extensions on the wall structure forming said inlet means bent forwardly over said front row of passages, and the flexible baffle structure on said outlet means comprises an upwardly and rearwardly inclined flexible deflector over said rear row of passages, said extensions partially overlapping when folded forward and being free of attachment to each other so that flexibility

thereof is not diminished and the baffle is continuous when the frame is flexed.

5. A goggles as defined in claim 2 wherein the flexible baffle structure over said inlet forming means comprises a plurality of forwardly extending laterally overlapping ears, said ears being readily bendable toward or away from the inlet end of said inlet forming means to control the volume of air admitted to the goggles.
- 10 6. In a goggles having a lens supported in a frame which has a flexible face contacting part cooperating with the lens to form substantially sealed eyecups when the goggles are worn the combination comprising, parallel ventilating air inlet and outlet forming means for said eyecups extending through the top edge of said frame, a transparent partition cooperating with the lens and frame to form a narrow space behind said lens communicating at its upper end with said 15 inlet forming means and adjacent its lower end with the space in the eyecup between the partition and the wearer's face, said inlet and outlet forming means comprising continuous strips of relatively flexible material formed to provide parallel rows of open passages defined by accordion folds in the strips and said strips having a plurality of extensions on the portions of said strips between said accordion folds including depending extensions forming back walls for the inlet forming means inclined forwardly to direct incoming air against the inner side of said lens and other extensions bent forwardly from the back sides of said inlet passages to form the baffle over the inlet ends of said inlet passages adapted to induce 20 a flow of air through the latter into the narrow space between said lens and partition, and a baffle on said outlet forming means comprising an accordion folded strip of material extending upwardly and rearwardly over the upper ends of 25 30 35 40 said outlet passages to limit egress from said passages to the rear side thereof.
